UNITED STATES PATENT OFFICE.

HENRY J. GAISMAN, OF NEW YORK, N. Y., ASSIGNOR TO AUTOSTROP PATENTS CORPORATION, OF DOVER, DELAWARE, A CORPORATION OF DELAWARE.

CARPET-WIRE BLADE-INSERTING MACHINE.

Application filed May 28, 1927. Serial No. 194,895.

The object of my invention is to provide means to remove used blades from and apply new blades to carpet wires, of the class used for cutting strands to produce knap or pile 5 on carpets and the like.

In carrying out my invention I provide a reciprocal member to push blades into position in the carpet wires, the blades preferably being supplied in a stack in a magazine 10 or holder, a movable support for the wires adapted to be moved into register with the blades to receive the latter, means to eject used blades from the wires as the latter are moved toward blade receiving position, and 15 means to move the support with a wire from and to blade receiving position.

My invention also comprises novel details of improvement that will be more fully hereinafter set forth and then pointed out in the 20 claims.

Reference is to be had to the accompanying drawings forming a part hereof, wherein

Fig. 1 is a plan view of a machine embodying my invention, the magazine for blades 25 being omitted;

Fig. 2 is a longitudinal section of Fig. 1, illustrating the magazine in position;

Fig. 2^a is an enlarged detail section of part of Fig. 1;

Fig. 2^b is a detail section on line 2^b, 2^b, in Fig. 2;

Fig. 3 is a detail view illustrating parts in a position different from that shown in Fig. 1;

Fig. 4 is a detail view illustrating the parts in position for ejecting a blade from the carpet wire;

Fig. 5 is a cross section on line 5, 5, in Fig. 2;

Fig. 6 is an enlarged detail section on line 6, 6, in Fig. 3;

Fig. 7 is an enlarged detail of part of the carpet wire;

Fig. 8 is a detail section on line 8, 8, in Fig. 1, and

Fig. 9 is a detail perspective of the blade magazine.

Similar numerals of reference indicate corresponding parts in the several views.

The carpet wire is indicated at A, which is of any usual or well known construction, shown provided with a recess or slot a at the blade receiving end, in which the blade B is located and retained by means of the spring-acting stop a', (Fig. 7). At 1 is indicated a

suitable support shown in plate-like form. A reciprocal member or pusher 2 is shown supported by and projects from a head 3 that is reciprocal in a guideway 4 carried by support 1. The guideway is shown provided between suitable blocks 5, 6, 7 and 8 carried by the support, whereby the parts 2 and 3 may be reciprocated. An operating member 9 is pivotally carried at 10 upon support 1 and shown provided with an arm 9^a for manipulating it and with an arm 9^b pivotally connected by link 11 with block 3, whereby when the member is rocked the block will be reciprocated to advance and retract the member 2. At 12 is a magazine or holder shown secured upon block or guide way cover 8 by screw 13, in which magazine the blades B are located in stacked relation over an opening 8^a in the part 8, beneath which opening is a rest 14 for the blades, the reciprocal member 2 being adapted to operate over said rest to push blades successively from the stack through the delivery end of the guideway, (Fig. 2). In order conveniently to handle the stack of blades B, I provide a blade holder shown comprising a flat piece of metal C having its end portions c, c' bent reversely, in hook-like form, to engage the adjacent corners of the triangularly shaped blades, and the side walls of the magazine 12 are provided with vertical recesses 12^a in which the portions c, c' of the holder C may be slid for conveniently locating the stack of blades in the magazine, (Fig. 9). A retainer D having its ends d bent laterally is adapted to be fitted against the plate C with the ends d opposing the upper and lower blades B of the stack for temporarily retaining the blades so that when the plate C with the blades has been placed in the magazine 95 the retainer D may be removed so that the blades may feed downwardly, whereby each time that the reciprocal member 2 is pushed under the stack a blade will be forced into a wire A, (Fig. 2^a). To receive the 100 blades B the wires A are temporarily held in opposition to the guideway 4 by means of a wire support 15 shown pivotally supported at 16 upon the support 1. The wire support 15 is shown provided with a longitudinal guideway 15' in which the adjacent portion of the wire may be placed in edgewise direction and upon the support 15 a retainer for the wire is provided. Said support 15 is shown provided with an inclined surface 15^a 110

for the wires A to retain their bent ends a'' in position for the blades B to slide thereover. The wire A is clamped and held at an acute angle to the feed of blade B so as to position the stop lug a' below the plane of the blade, which will flex to pass over said stop lug to enter slot a in the wire, (Fig. 2^a). Said retainer is shown in the form of a stud 17 journaled on the support 15 and having a finger 18 piece 17' for rotating it, the stud being retained by means of a nut 18, (Fig. 2^b). The retainer 17 is shown provided with an eccentric annular edge portion 17^a and a flange 17^b over the latter, whereby the retainer may be rotated to present the narrow part of the eccentric 17^a opposite the guideway 15' to permit the insertion into and the removal of wire A from said guideway. When the retainer is rotated farther its greater eccentric portion will push the wire against the back of the guideway and the flange 17^b will overlie the wire to retain it in firm position with its recess a in opposition to the guideway 4 in position to receive blade B when pushed from said guideway, (Fig. 1). The blade support 15 is operative by the actuating member 9 in correspondence with the operation of the reciprocative member 2, for which purpose I have shown a rod 19 pivotally connected at 20 with arm 9' of member 9 and slidable in a bore in a stud 21 journaled on an arm 15^a projecting from member 15. A spring 22 upon said rod opposes stud 21 and also opposes a nut 23 on rod 19, whereby the tension of the spring may be adjusted, a nut 24 on the outer end of the rod being adapted to bear against the stud for actuating member 15 in one direction, the spring 22 serving to resiliently actuate member 15 in the opposite direction and permit sliding of rod 19. An arm 25 is pivotally supported at 26 and is provided with a grooved roller 27 at the free end adapted to engage the sides of the blade adjacent to the cutting edge with the latter in the groove of the roller so as not to be dulled, (Fig. 6). A spring 28 secured at 29 normally presses arm 25 and its roller toward blade B, and a stop 30 engaging said arm limits the movement of the roller toward the blade, (Figs. 1 and 3). The spring pressed roller 27 tends to guide the blade and keep the back of the blade snugged against the adjacent portion of guideway 4 when the blade is being pushed from the latter into the wire A.

A blade ejector is indicated at 31 shown comprising an arm pivotally supported at 32 on support 1 and normally retained by a spring 33 (connected with said ejector and said support) against a stop 34 on said support, (Fig. 1). The ejector 31 is located so that the member 15 with the wire A may pass beneath the ejector and said ejector is provided with a downwardly extending lug 31^a, located adjacent to one side of the ejector,

(Fig. 8). The ejector 31 is also provided with a spring-acting finger 35 shown secured to the ejector by screw 36 and extending inclined in a direction toward the side of the ejector opposite lug 31^a with the free end 35^a of said spring finger extending upwardly normally against the adjacent edge of the ejector, (Fig. 8), to be engaged by the blade support 15.

When a blade is to be removed from a carpet wire A and another blade inserted in the wire the operating member 9 will be moved to approximately the position shown in dotted lines in Fig. 1, whereupon the carpet wire support 15 will be also moved to the dotted position shown in said figure opposing a gauging stop 37 on support 1, and the reciprocative member or pusher 2 will be fully retracted from beneath the stack of blades. The wire A will then be placed in its support 15 and the tip end of the wire will be brought against gauge 37 to position the wire and the latter will be fastened by the retainer 17. The operating member 9 will then be rotated toward the full line position shown in Fig. 1. As member 15 is moved with member 9 the ejector lug 31^a will engage the blade in the wire and cause its ejection from the wire, (Fig. 4), and continued movement of member 15 will cause it to pass under spring finger 35 and bring the member to rest against stop 38 with the wire in position to receive a blade, and continued operation of member 9 will cause the reciprocative member 2 to push the lowermost blade in the stack into the recess a in wire A to a position behind the stop a' of the wire, (Figs. 3 and 7). The member 9 next will be moved toward the dotted line position in Fig. 1, and as the member 15 is correspondingly moved said member 15 will engage spring finger 35 and cause the ejector 31 to be swung around on its pivot 32 to the dotted line position without engagement of the blade edge with said spring finger, and during such movement of the ejector its lug 31^a will be moved in advance of the blade on the carpet wire so as not to interfere with the latter. When the member 15 has released the finger 35 the ejector will be swung back against stop 34 by spring 33 to the full line position in Fig. 1. The carpet wire A having the blade attached may be removed from member 15 and a new wire inserted, and so on.

In accordance with my invention old or used blades may be removed from carpet wires and new blades fitted in said wires successively and expeditiously, whereby economy in time is effected in the operations, handling of the blades by the operator is avoided, and the blades will all be accurately set in the wires.

Having now described my invention what I claim is:

1. A machine of the character described

comprising supporting means for carpet wires, means to insert blades in the wires, means to move said supporting means to and from blade receiving position, and means to eject blades from the carpet wires before the latter are brought to blade receiving position.

2. A machine of the character described comprising supporting means for carpet wires, means to supply blades for the wires, means to successfully insert the blades in the wires, and devices to move the wire supporting means from blade receiving position for ejection of the blades from the wires and to blade receiving position to insert blades into the wires when the latter are in the last named position.

3. A machine as set forth in claim 2, provided with an ejector for the blades located in position to engage the blades and eject them from the wires when the latter are out of blade receiving position.

4. A machine as set forth in claim 2, provided with an ejector for the blades located in position to engage the blades when the wires move toward blade receiving position.

5. A machine as set forth in claim 2, provided with an ejector for the blades movably supported with respect thereto, said ejector having means to engage blades to eject them from the wires when the latter move in one direction respecting the blade inserting means.

6. A machine as set forth in claim 2, provided with an ejector for the blades movably supported with respect thereto, said ejector having means to engage blades to eject them from the wires when the latter move in one direction respecting the blade inserting means, said ejector to be operated by and with the movement of the blade support in a different direction to prevent engagement of a blade with the ejector when the blade moves in the last named direction.

7. A machine of the character described comprising a movable carpet wire support, means to detachably secure carpet wires on said support, means to supply blades for the wires, a reciprocative member to insert blades in the wires, an operative member, and means connecting the operating member with the blade support and with the reciprocative member for moving the wire support out of blade receiving position to receive successive wires and to move said support to blade receiving position and operate the

reciprocative member to insert blades in the wires successively.

8. A machine as set forth in claim 7, provided with an ejector located in position to engage blades and eject them from the wires when the latter are out of blade receiving position.

9. A machine as set forth in claim 7, provided with an ejector having a lug to engage the blades to eject them from the wires when the latter are out of blade-receiving position, said ejector being provided with means operative by and with the wire support to move said lug out of blade engaging position when the wires move from blade receiving position.

10. A machine as set forth in claim 7, provided with a pivotally supported ejector, a spring to operate said ejector in one direction, a stop for the ejector, and a lug carried by the ejector to engage blades in said wires when the latter move toward blade receiving position, said ejector having means to be operated with the blade receiver to move said lug out of the path of new blades on the wires.

11. A machine of the character described comprising a pivotal carpet wire support, means to removably secure carpet wires thereon, means to supply blades for the carpet wires, a reciprocative pusher to insert blades in the wires, an operative member, and means operatively connecting said member with said reciprocative pusher and with said blade support for moving the support from blade receiving position to a position for ejection of blades from the wires and to blade receiving position and advancing the pusher to insert blades in the wires.

12. A machine as set forth in claim 11, provided with a resiliently operative arm adjacent to the blades and provided with a grooved roller to engage the blades for guiding them to the wires.

13. A machine as set forth in claim 11, provided with a pivotally supported ejector provided with a lug to engage blades when the wire support moves toward blade receiving position, said ejector having a spring-acting finger to be operated by movement of the wire support when moving away from blade receiving position to move the lug out of the path of the blades, said finger permitting the wire support to pass the ejector when moving toward blade receiving position.

HENRY J. GAISMAN.
